US0D1099727S

(12) **United States Design Patent** (10) **Patent No.:** **US D1,099,727 S**
(45) **Date of Patent:** **** Oct. 28, 2025**

(54) **ANALYZER DEVICE**

(71) Applicant: **GrainSense Oy**, Oulu (FI)

(72) Inventor: **Jussi Helminen**, Oulu (FI)

(73) Assignee: **GrainSense Oy** (FI)

(**) Term: **15 Years**

(21) Appl. No.: **35/518,743**

(22) Filed: **Jun. 29, 2023**

(80) **Hague Agreement Data**

Int. Filing Date: **Jun. 29, 2023**

Int. Reg. No.: **DM/232268**

Int. Reg. Date: **Jun. 29, 2023**

Int. Reg. Pub. Date: **Oct. 20, 2023**

(30) **Foreign Application Priority Data**

Dec. 29, 2022 (EM) 015007653-001

(51) **LOC (15) Cl.** **10-04**

(52) **U.S. Cl.**

USPC **D10/81; D10/75**

Primary Examiner — Christian P. McLean

Assistant Examiner — Sara S Sahneh

(57) **CLAIM**

The ornamental design for an analyzer device as shown and described.

DESCRIPTION

1. Analyzer Device

1.1 Rear View

1.2—Bottom View

1.3—Front View

1.4—Perspective View

1.5—Left View

1.6—Right View

1.7—Top View

The broken lines shown are included for the purpose of illustrating portions of the analyzer device that form no part of the claimed device.

1 Claim, 7 Drawing Sheets
